UNITED STATES PATENT OFFICE.

ELMER F. SEAGER, OF DETROIT, MICHIGAN, ASSIGNOR OF ONE-HALF TO ROBERT C. STURGEON, OF WINDSOR, CANADA.

CONDENSER.

Application filed October 6, 1921. Serial No. 505,744.

To all whom it may concern:

Be it known that I, ELMER F. SEAGER, a citizen of the United States of America, residing at Detroit, in the county of Wayne 5 and State of Michigan, have invented certain new and useful Improvements in Condensers, of which the following is a specification, reference being had therein to the accompanying drawings.

10 This invention relates to a condensing apparatus and has special reference to an apparatus that may be advantageously used as part of a refrigeratory system for condensing ammonia gas or vapor.

15 The object of this invention is to provide a compact condenser for a refrigeratory apparatus by which ammonia gas or vapor may be expeditiously condensed, the condenser including a main tank containing a 20 cooling agent, an outer coil in the tank, an inner coil in the outer coil and communicating with the tank, and a receiver in the tank communicating with the outer coil. This arrangement provides primary and secondary 25 cooling zones with the latter zone serving functionally as a sealing agent about connections forming part of the primary cooling zone.

The above and other objects are attained 30 by a construction that will be hereinafter described and then claimed, and reference will now be had to the drawing, wherein

Figure 1 is a longitudinal sectional view of the condensing apparatus, partly in elevation, and

Fig. 2 is an end view of a portion of the apparatus.

In the drawings, the reference numeral 1 denotes a main tank or receptacle having 35 end walls 2 and 3 and before these walls are placed in position the greater part of the apparatus is assembled within the tank or receptacle, and the interior thereof constitutes a secondary cooling zone adapted to receive a cooling agent, as water, from a pipe 4 connected to the tank at one end thereof.

Suitably mounted within the main tank 1, in spaced relation to the walls thereof, is an outer coil of tubing 5 which has one end convolution thereof connected to a coupling member 6 and the other end convolution connected to a coupling member 7. The coupling member 7 has a conventional form of stuffing box 8 and extending through said stuffing box is the open end 9 of an inner coil of tub-

ing 10, said inner coil of tubing being disposed throughout the outer coil of tubing 5 in spaced relation to the tubing, so as to provide a passage 11 between the coils of tubing 5 and 10. The opposite end 60 of the inner coil of tubing 10 extends through a stuffing box 12 of the coupling member 6 and then through the end wall 2 of the main tank. With the inner coil of tubing 10 open adjacent the coupling member 7 and communicating with the main tank, it is obvious that the water within the tank can flow through the inner coil of tubing 10 and provide what I term a primary cooling device, 65 with the passage 11 between the coils of tubing serving as a primary cooling zone.

Extending through the end wall 2 of the main tank and connected to the coupling member 6 is a gas or vapor inlet pipe 13 and said coupling member has a chamber 14 70 which permits of the gas and vapor from the pipe 13 entering the primary cooling zone or passage 11 between the coils of tubing 5 and 10.

The coupling member 7 has a chamber 15 75 to receive the gas or vapor from the passage 11 and connected to the coupling member 7 is a pipe 16 leading to a receiver or secondary cooling device 17 which is placed concentric of the coil of tubing 5, in spaced relation thereto and preferably against the end wall 3 of the main tank 1. The receiver 17 has a suitable outlet pipe 18 extending from a point adjacent the inner end of the receiver through the outer end thereof and 80 through the end wall 2 of the main tank 1.

With the circulation of water or other cooling agent maintained through the main tank 1 it is obvious that the outer coil of tubing 5 and the receiver 17 are cooled by 85 the water and by circulating the water through the inner coil of tubing 10, the gas or vapor in the passage 11 and the receiver 17 will be cooled and condensed.

I attach considerable importance to the 90 compact manner in which the greater part of the apparatus is arranged within the tank, and since this tank may be water and air tight there is very little danger of ammonia or other injurious gases escaping.

With the receiver containing the liquefied 95 vapor, the liquid may be maintained in a cool state for a low condensing pressure. For instance with the cooling agent of the 100 secondary zone at approximately sixty-eight 105 110

degrees, Fahrenheit, a condensing pressure as low as one hundred and fifteen is obtainable, and probably lower, which is a desideratum with all condensing systems.

5 One embodiment of my invention has been illustrated, but it is to be understood that the structural elements are susceptible to such changes, in size, shape and manner of assemblage as fall within the scope of the 10 appended claims.

What I claim is:—

1. A condensing apparatus comprising a main tank adapted to receive a cooling agent, a receiver in said main tank, an outer coil about said receiver and communicating therewith, and an inner coil in said outer coil and communicating with said main tank.

15 2. A condensing apparatus as in claim 1, and coupling members supporting said outer

coil and through which the ends of said 20 inner coil extend.

3. In a condensing apparatus wherein 25 coils of tubing, one within the other, afford a cooling zone for vapors by circulating a cooling agent in the innermost coil of tubing; means for condensing such vapors as escape liquefaction in the cooling zone, comprising a receiver to receive the uncondensed vapor, and means for utilizing the cooling agent for cooling the receiver in advance of 30 utilizing it in the aforementioned cooling zone.

In testimony whereof I affix my signature in presence of two witnesses.

ELMER F. SEAGER.
